CLAIM

The ornamental design of an adjustable plant and knick-nack stand combination, as shown.

DESCRIPTION

FIG. 1 is a front elevational view of an adjustable plant and knickknack stand combination showing our new design;

FIG. 2 is a right side elevational view thereof;

FIG. 3 is a left side elevational view thereof;

FIG. 4 is a back elevational view thereof;

FIG. 5 is a top plan view thereof;

FIG. 6 is a bottom plan view thereof;

FIG. 7 is a front elevational view thereof with the shelves in an alternate arrangement; and,

FIG. 8 is a right side elevational view of FIG. 7.

FIG. 4

FIG. 3

FIG. 2

FIG. 1
